UNITED STATES PATENT OFFICE.

WILLIAM J. KELLEY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

FRAME STRETCHER.

Application filed December 18, 1922. Serial No. 607,615.

This invention relates to improvements in frame stretchers and has particular reference to a novel and improved construction of mechanism adapted for use in the stretching or formation of non-metallic ophthalmic mountings.

One of the principal objects of the present invention is the provision of an improved heat actuated stretching device which will eliminate the difficulties hitherto experienced and permit of ready and accurate stretching of a non-metallic ophthalmic lens rim to desired size.

A further object of the present invention is the provision of a heat controlled device in which the element of time does not need to be considered, in which over-heating of the frame is prevented, and in which over stretching of the frame due to twisting movement, or the like, is also eliminated.

A further object of the invention is the provision of an improved automatic device for stretching non-metallic frames to desired size.

Other objects and advantages of the present invention should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a side elevation of one embodiment thereof,

Figure II represents a vertical sectional view thereof,

Figure III represents a sectional view of a modified form of the invention,

Figure IV represents a detail section indicating the means for adjusting the supporting table, and

Figure V represents a slightly different size stretching and controlling mechanism.

In the drawings, in which similar characters of reference are employed to denote corresponding parts throughout the several views, the numeral 1 designates the base of my improved stretcher having mounted thereon the stationary frame block 2 and supplemental base portion 3, on which is secured half of the stepped former shell 4 having a plurality of steps 5 with inter-

mediate frame receiving portions 6, the whole forming a substantially cone like member having cylindrical portions of gradually decreasing diameter. Slidably mounted upon the member 2, as is clearly illustrated in Figures II and III, is a slide 7 bearing the block 8, to which is secured a second correspondingly shaped stretcher shell designated as an entirely by the numeral 9, having the portions 5 and 6 as before. This slide has an interior passage 10 in which is located the compression spring 11 bearing at one end against the end of the slide and at the other end against the block 12, retained in place by the set screw 13 extending upward from the base or frame portion 2. The member 2 is further provided with the upstanding lug 14 in which is rotatably mounted the size controlling screw 15. It will be noted that the two stepped cylindrical stretcher members are formed of thin metallic material adapted to have fitted therearound in engagement with the correct member 4 and resting on the proper step 5 the composition eye or frame 17, while contained within said members is a suitable source of heat such as the electric light bulb 18, the radiation properties of the metal shaping members and the heat given off by the bulb 18 being so proportioned that the bulb will quickly heat the members 9 and 19 to a point where the heat of conduction will soften the frame 17 but below a point which will in any way damage or injure said frame if left in place for a considerable period. In use the frame having been put in position on the proper step 5 the adjusting screw 15 is backed up away from the slide 7 substantially the amount that it is desired to stretch the frame, either for a larger size lens or merely to open out the frame so that the proper size lens may be inserted in position within it, and the bulb or source of heat is energized. The spring 11 will tend to expand forcing the members 9 and 19 apart as the member 17 is softened and yields until further movement of the member 7 is prevented by its contact with the limiting stop 15 carried by the portion 14 of the base 2. The parts will then stay in this predetermined position without increase of size or distortion until the workman is ready to remove the frame.

To prevent any distortion due to twisting, I make use of a vertically adjusting table

member 20 carried as by the standard or support 21 slideable in the tube 22 on the base, and which may be locked in adjusted position as by the cone point 23 adapted to 5 be engaged in one of the notches or sockets 24 in the standard 21 according to the particular step 5 on which the other part of the frame was to rest, this cone point being inwardly actuated as by the spring 26, while 10 having the hand piece 27 by which it may be withdrawn from locking engagement against the pressure of the spring.

In Figure III, I have shown a slight modification in which in place of using the 15 members 9 and 19 on which to stretch the frame, one or both of the members 28 and 29 may be removably held in position on their respective base portions as by the thumb nuts or clamps 30, the parts being 20 then interchanged according to the size of eye to be stretched, the action being otherwise the same as previously described.

In Figure V, I have shown another slight 25 modification of my invention, in which in place of an expanding compressed spring I make use of the tension spring 31 and the stop or limiting screw 32 used in the same manner as was the screw 21 of Figures II and III.

30 To facilitate operation of the device if desired there may be suitably pivoted to the base 1 or to the tube or support 22, for example, rising therefrom, a control lever or handle 33 having a tongue portion 34 bearing 35 against the rear of the block 8 on the

slide 7, grasping of this handle and swinging it on its pivot serving to force the member 8 and thus the slide and mandrel section 9 carried thereby toward the fixed mandrel section 19 closing up the split mandrel for 40 positioning of a frame thereon or holding the parts closed to facilitate removal of a frame therefrom.

I claim:

1. A device of the character described, including a stepped expansible mandrel and a table adjustably mounted adjacent the mandrel for cooperation with the various steps thereof. 45

2. A device of the character described, including a stepped expansible mandrel and a table adjustably mounted adjacent the mandrel for cooperation with the various steps thereof, and means for locking the table in desired adjusted position. 50

3. A device for stretching an ophthalmic frame, comprising a base, a mandrel section on the base, a slide on the base, a second mandrel section on the slide movable therewith, resilient means to normally urge the 60 slide and mandrel section thereon away from the mandrel section on the base to stretch one eye of the frame, means to restrict the separation of the mandrel sections to stretch the ophthalmic frame to predetermined size, means to heat the said mandrel sections, and an adjustable table for supporting that part of the ophthalmic frame not being stretched. 65

WILLIAM J. KELLEY.
